UNITED STATES PATENT OFFICE.

HENRY HOOVER HANGER, OF WASHINGTON, DISTRICT OF COLUMBIA.

ARTIFICIAL LIMB.

1,151,520.

Specification of Letters Patent. Patented Aug. 24, 1915.

Application filed November 5, 1914. Serial No. 876,821.

To all whom it may concern:

Be it known that I, HENRY HANGER, a citizen of the United States, and a resident of Washington, District of Columbia, have invented new and useful Improvements in Artificial Limbs, of which the following is a specification.

My invention relates to artificial limbs, and pertains more particularly to artificial legs of the character shown in United States Patent No. 907,146, granted to myself December 22, 1908.

The object of my invention is to produce an artificial leg of the type described in which the ankle portion is made of two sections adapted to be readily separated to permit the substitution of another lower or ankle section of different length to adjust the length of the limb to suit the wearer.

Another object thereof is to produce an ankle section separably secured on the leg portion provided with a forwardly projecting instep lever adapted to coöperate with the pivoted foot to control the action thereof, and a still further object thereof is to produce a more simple, cheap and efficient artificial limb of the character shown than has heretofore been attained.

To these ends my invention includes the combination and arrangement of component parts to be hereinafter described and more particularly pointed out in the claim.

In the accompanying drawings, in which like reference characters indicate similar parts, Figure 1 is a vertical sectional view of my invention, and Fig. 2 is a bottom plan view of the end portion of the lower leg.

Referring to the drawings, I indicates the lower leg portion of an artificial limb which is preferably made of light strong wood, such as willow and is hollowed or bored at 2 from the top down to the angle portion 3.

For the purpose of permitting the adjustment and change in the length of the limb, I provide a separate end portion 4 for the leg, which as shown, comprises the main body portion 5 and the forwardly extending downwardly inclined instep lever 6. The main body portion of said end conforms to the contour of the ankle of the leg, and is secured on the leg by the bolt 7 and the dowel pin 8, and the contacting faces may be glued together. Said end portion is pref-

erably made of hard wood, such as hickory, and is cut in such manner that the grain of the wood is longitudinal of the lever 6 while the grain runs diagonally of the main body portion 5. I do not, however, confine the material of the end portion to wood, as I have found that same may be made of aluminum or similar metal molded to conform to the contour of the leg, or of wood fiber.

It will be appreciated that the end portion 4 may be readily and conveniently removed and replaced by another of similar design, but of greater or less length to accommodate the length of the leg to the comfort of the wearer. This adjustability is particularly advantageous for growing children, and permits the regulation of the artificial leg to the growth of the natural limb.

The foot portion 9 is hinged to the ankle portion in any suitable manner. In the preferred manner shown, a pintle 10 is secured to the ankle portion by the bolts 11 which pass upward through the removable end portion 4 and the integral part of the ankle portion into the hollow portion thereof where they are engaged by nuts. Passing over the pintle 10 is a yoke 13 whose lower arms pass downward through the wood of the foot portion 9 and are engaged by nuts 14 thereby securely locking the foot to the ankle portion, but permitting the rocking of the foot to a limited extent on the pintle 10.

The heel portion has formed therein a vertical opening 15 extending entirely through the heel from the top to bottom which opening is flared from the bottom upwardly. Over the lower end of the opening is secured a leather covering 16, preferably of buckskin, and this covering may be cushioned in any suitable manner.

In the rear lower face of the end portion 4 is formed a socket 17. A piece of rubber 18, which is round in cross-section, is carried in the vertical opening 15 in the heel portion, resting on the covering 16 at its lower end, while its upper end is seated in the socket 17 before mentioned.

As shown in the drawings, a recess 19 is formed in the foot in front of the ankle hinge for the reception of the projecting end of the lever 6, in the bottom of which is

formed an enlarged socket 20 for the reception of the rubber cushion 21 on which the lever bears.

Having thus described my invention, what I claim as new, and desire to be secured by Letters Patent, is—

In an artificial limb, a lower leg portion, a lower end portion removably secured

thereon, a forwardly extending instep lever on said end portion, and a foot-piece hinged **10** to said leg, substantially as described.

H. HOOVER HANGER.
